UNITED STATES PATENT OFFICE.

JAMES W. BRYCE, OF BINGHAMTON, NEW YORK, ASSIGNOR TO THE INTERNATIONAL TIME RECORDING COMPANY OF NEW YORK, A CORPORATION OF NEW YORK.

SYNCHRONIZING-CLOCK SYSTEM.

1,388,167.

Specification of Letters Patent. Patented Aug. 23, 1921.

Application filed December 30, 1920. Serial No. 433,976.

To all whom it may concern:

Be it known that I, JAMES W. BRYCE, a citizen of the United States, residing at Binghamton, in the county of Broome and 5 State of New York, have invented certain new and useful Improvements in Synchronizing-Clock Systems, of which the following is a full, clear, and exact description.

In an application filed by me on August 10 24, 1920, Serial Number 405,607 I have shown and described a synchronizing clock system of novel character, in which a master clock is used to control the operation of a plurality of secondary clocks, and to bring 15 such clocks at stated and definite instants into perfect synchronism with itself in case for any cause they are not in such exact accord, but are either too fast or too slow.

This system requires for its successful operation a special arrangement of electric circuits and connections particularly so if the system be one in which both direct and alternating currents must be utilized in its operation. For example, in a factory plant, 20 the power for operating the system may be obtained from a direct current source supplied by the local power plant during the day or working hours. At other times, however when the plant is not running it may 25 be necessary to draw on the municipal circuits for power, and these may be from an alternating source.

The circuits which I contemplate using in my system are specially designed and 30 adapted to operate the now well known Bryce synchronizing apparatus, and while they have no broadly distinctive features of novelty, they are new in their character and arrangement to the extent which may 35 best be indicated by the specific description contained in the following specification in which reference is made to the accompanying drawings.

Figure 1 is a view in front elevation of 40 the master clock employed in the system.

Fig. 2 is a view in elevation of a special form of circuit controller used therein.

Fig. 3 is a top plan view of the same.

Fig. 4 is a detail of a supplemental circuit controller.

Fig. 5 is a diagram of the circuits used in the system when supplied by direct current and

Fig. 6 is a similar diagram showing the 50 arrangement of circuits and devices re-

quired when both direct and alternating currents are used in the operation of the system.

It is essential to an understanding of the invention to know that the master clock is 60 an accurate time piece which may be kept running indefinitely, for which purpose I prefer to use the clock which I have described in detail in the copending application above referred to. This clock is 65 equipped with two circuit controllers. One of these shown in Figs. 2 and 3, comprises two cams 1 and 2 on the hour shaft and two levers 3 and 4, which are spring actuated and which bear upon the peripheries of the 70 the said two cams or cam disks. The lever 3 carries an insulating plate 5, to which is attached a metal plate 6, carrying contact points 7 and 8. The other lever 4, carries an insulating plate 9, to which is secured a 75 metal plate 10, also having two contact points 11, 12, between which the plate 6 oscillates.

Normally the plate 5, lies midway between the two contacts 7 and 8, but at fifteen minutes of the hour the lever 3 is shifted by its cam on the hour shaft, throwing its right hand contact 7 into engagement with the corresponding contact 12. In like manner, at the even hour the lever 4 is 80 shifted by its cam, which throws the left hand contact 11 into engagement with the contact 8 and breaks the contact between 85 7 and 12. The purpose and function of this operation will be understood from the description of the system hereinafter given.

The relative slowness of the hour shaft may not be depended upon for closing the circuit to line at exactly the correct instant required, and I therefore use in conjunction with the circuit controller above described, a supplemental circuit controller operated by a cam 13, on the minute shaft. This cam brings together two contacts 14 90 and 15 during a certain part of each minute 95 and then separates them, and its function 100 will be also understood from the description of the system which follows:

In this system the master clock connects to the line, with which any number of secondary clocks are connected, a source of current. Each secondary is provided with two circuits 16 and 17 containing magnets 18 and 19 and other devices, and if the clock be too slow, one of these circuits is con- 105 110

nected to line so that an accelerating device therein will operate to speed the clock up until it catches up with the master clock, or if it be too fast the other circuit is connected 5 to line and operates to retard the clock until the master clock has caught up to it. This operation is performed by a circuit controller 20 operated by a cam 21 and driven by the secondary train.

10 Referring now to Fig. 5, 22, 23 are the terminals of the power circuit. At fifteen minutes of each hour the lever 3 is shifted to bring contacts 7 and 12 together and this 15 operates to connect the wire 24 from terminal 22 and connected to contact 12 to the wire 25, which by the closure at the exact minute of the controller contacts 14 and 15 is continued to a relay magnet 26, thence through resistance unit 27 and thence to the 20 opposite terminal 23. The relay being thus energized attracts its armature 28 which connects wire 29 from terminal 22 to the line wire 30 and also closes the source through the resistance unit 27 and the relay 25 magnet 26. The path through wire 25 will soon be broken by the cam 13 or might be interrupted in the master clock for some other reason, but this has no effect on the 30 operation of the relay 26 which remains closed until the main circuit controller again operates.

The source of current therefore remains connected with the line until the even hour or for fifteen minutes. At the latter instant 35 the lever 4 breaks the contact between 7 and 12 and closes that between contacts 8 and 11, and this operates to close a short circuit around the relay 26 through wires 31 and 25, hence the relay magnet is deenergizing 40 and its armature falls away disconnecting the source from the line.

If both direct and alternating currents are supplied to the line for operating the synchronizing mechanism special provision 45 must be made therefor, because it is practically impossible to wind magnets which are capable of operating properly on both direct and alternating currents. To approximate to the necessary conditions the magnets are 50 wound for low resistance and low inductance, and a relatively high non-inductive resistance used in series with them, which is tapped so that when an alternating current is used, there is less resistance in series with 55 the magnet or magnets than when a direct current is supplied. This is illustrated in Fig. 6.

In this figure, using different reference numerals wherever necessary to avoid confusion, a selector relay 32 is connected directly across the terminals 22 and 23, and a resistance unit 33 included in series with it. The magnet of this relay is of very high inductive resistance so that it responds only 60 to a direct and not an alternating current.

The relay has two armatures 34 and 35, one connected with wire 36, from the contact 11, the other with wire 37, from the contacts 7 and 8. The terminal 22 is connected, as before, with the contact 12.

When a direct current comes from the source, the two armatures 34 and 35 are raised; hence when the circuit through wire 37 is closed a relay magnet 38 is energized by the current which finds its way back to 70 terminal 23 through a resistance 39. This relay, like relay 26 of Fig. 5, connects the source to line through a resistance 45 and also closes the source through itself by connecting wire 29 to wire 40 containing the 75 magnet and resistance 39. The operation is thereafter the same as in the case of Fig. 5. If the source be alternating, selector relay 32 is not energized, and hence by the master 80 clock circuit controller the source is connected to relay 41 and through resistance 42 to the terminal 23. This relay in addition to closing its own circuit independently of the master clock circuit connects the alternating source to the secondary clocks through 85 a circuit wire, which is connected to an adjustable contact 44 that includes less than 90 the whole of the resistance 45.

By this means it becomes possible and practicable to use such magnets 18 and 19 in 95 the secondary clocks as will be properly operated either by a direct or by an alternating current, and the system is made applicable to both kinds of current. The distinction between Figs. 5 and 6, it will be observed, 100 resides in the use of two relays, similar to the one used in Fig. 5, with appropriate means for operating through one or the other, as the case may be, to secure the desired results.

What I claim as my invention is:

1. In a synchronizing clock system, the combination with a source of operating current, of a master clock, a circuit from the source to the same, a relay, a resistance and a circuit controller operated by the master 105 clock in such circuit, said circuit controller being adapted to close such circuit for definite intervals of time, means operated by the relay for closing the circuit from the source through said resistance and its own magnet 110 and for connecting said source to the line, and means operated by the master clock for throwing said relay out of action at the end of the periods of closure by the circuit controller therein.

2. In a synchronizing clock system, the combination with a source of operating current, of a master clock, a circuit controller operated thereby during given intervals to close a circuit from the source, two paths or circuits adapted to be connected to the said circuit, a selector relay in a closed circuit from the source adapted to be energized by a direct current only for connecting one or the other of such circuits with the source,

- relays in said paths or circuits and means
operated thereby for connecting the source
to the line through paths adapted for direct
or for alternating currents, respectively, and
5 for closing the circuit from the source
through their own magnets, and means op-
erated by the master clock for throwing said
relays out of operation at the ends of the in-
tervals of closure by its circuit controller.
10 3. In a synchronizing clock system, the
combination with a source of operating cur-
rent and a circuit from the same, of a master
clock, a circuit controller operated thereby
to close said circuit for definite intervals,
- and a supplemental circuit controller oper- 15
ated thereby for making and breaking the
said circuit at frequent intervals, a relay in
the circuit so controlled adapted by its op-
eration to close the source through its own
magnet and also to connect the source to line, 20
and means operated by the master clock at
the end of the definite periods of closure by
its circuit controller to throw the relay out
of action.

In testimony whereof I hereunto affix my 25
signature.

JAMES W. BRYCE.
